US00D702695S

(12) **United States Design Patent**
Sun et al.

(10) **Patent No.:** US D702,695 S
(45) **Date of Patent:** ** Apr. 15, 2014

(54) **MEMORY DEVICE**

- (71) Applicant: **Biwin Storage Technology Limited**, Shenzhen (CN)
- (72) Inventors: **Rixin Sun**, Shenzhen (CN); **Wei Lu**, Shenzhen (CN); **Zhenhua Li**, Shenzhen (CN); **Lin Hu**, Shenzhen (CN); **Yafei Wang**, Shenzhen (CN)
- (73) Assignee: **Biwin Storage Technology Limited**, Shenzhen (CN)
- (**) Term: **14 Years**
- (21) Appl. No.: **29/454,207**
- (22) Filed: **May 8, 2013**

(30) **Foreign Application Priority Data**

Nov. 8, 2012 (CN) 2012 3 0540634

- (51) **LOC (10) Cl.** **14-02**
- (52) **U.S. Cl.**
USPC **D14/436**
- (58) **Field of Classification Search**
USPC D14/435–438, 478–480, 480.1–480.7; 235/441, 443, 487, 492, 493, 495; 361/737, 679, 752, 736, 728, 796, 797, 361/729, 730, 725–727; 257/678, 679, 693, 257/E23.064; 439/946, 948, 159; 174/250, 174/260, 52.1, 52.2; 710/300–303; 438/121

See application file for complete search history.

Primary Examiner — Susan Moon Lee

(57) **CLAIM**

The ornamental design for a memory device, as shown and described.

DESCRIPTION

FIG. 1 is a front view of a first embodiment of a memory device;

FIG. 2 is a rear view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

1 Claim, 7 Drawing Sheets
